CLAIM

The ornamental design for a console for data processing equipment, substantially as shown and described.

DESCRIPTION

FIG. 1 is a perspective view of a console for data processing equipment showing my new design;

FIG. 2 is a top view thereof;

FIG. 3 is a front view thereof; and

FIG. 4 is a side view thereof.

The sides are identical, and the rear is identical to the front.

FIG.1

FIG.2

FIG.3

FIG.4
